UNITED STATES PATENT OFFICE.

ELMER C. PARSONS, OF LITCHFIELD, MINNESOTA.

AEROPLANE.

1,141,002.

Specification of Letters Patent. Patented May 25, 1915.

Application filed September 22, 1914. Serial No. 362,987.

To all whom it may concern:

Be it known that I, ELMER C. PARSONS, a citizen of the United States, residing at Litchfield, in the county of Meeker and State of Minnesota, have invented new and useful Improvements in Aeroplanes, of which the following is a specification.

This invention relates to aeroplanes, and its primary object is to provide a simple, reliable and efficient construction of aeroplane which shall be inherently self-balancing, both laterally and longitudinally.

A further object of the invention is to provide an aeroplane structure in which front and rear supporting surfaces, each consisting of laterally-extending wings, are arranged both fore and aft of a car or carriage sustaining the load weight, and are carried by dihedrally-angled head and tail frames, whereby the points of support upon the air, when the machine is in flight, are at a level above and equidistantly in front and rear of the load weight, so that the resistance of the load weight to deflection from its normal position, as well as the lateral and longitudinal dihedral disposition of the wings, will result in a self-righting action in the event of the balance of the machine being at any time disturbed by reason of unequal air pressures, upon the respective parts of its supporting surfaces.

The invention consists of the features of construction, combination and arrangement of parts herein fully described and claimed, reference being had to the accompanying drawings in which:

Figure 1 is a front elevation of an aeroplane embodying my invention. Fig. 2 is a side elevation of the same. Fig. 3 is a top plan view of the same. Fig. 4 is a top plan view of the carriage. Fig. 5 is a longitudinal section through the car and a portion of the frame. Fig. 6 is a vertical transverse section through the car.

In the practical embodiment of my invention, I provide a main frame structure 1 in the form of a car, carriage or platform to receive or support the seats for the aviator and passengers, if any, the driving motor or motors 2, and the control devices, which last may vary in number and arrangement according to the character and number of rudders employed. The base of this car or carriage is provided with suitable wheels 3 to support the central portion of the machine, when said machine is at rest upon

the ground. The driving propeller 4 is suitably mounted at the top of the frame structure of the car or carriage upon a horizontal longitudinal shaft 5, which is preferably provided on opposite sides of the propeller with sprocket gears 6 connected with a pair of drive chains 7 driven from gears 8 which receive motion from the motor or motors 2, but any desired construction and arrangement of propeller and drive gearing may be employed.

Projecting from the frame of the car or carriage are head and tail frames 9 and 10, which may be of square or other suitable formation, and which in accordance with my invention respectively project upwardly and forwardly and upwardly and rearwardly at an angle of about 15° to the car or carriage, said head and tail frames thus being arranged at a dihedral angle with relation to each other. The said head and tail frames are provided at their outer extremities with depending brackets 11 carrying suitable wheels and skids 12 arranged in the horizontal plane of the wheels 3, whereby said head and tail frames are supported at their outer extremities from the ground when the machine is at rest.

The head and tail frames are provided with supporting surfaces 13 and 14 and carry horizontal and vertical rudders 15 and 16, which rudders are connected in practice with suitable control devices arranged upon or within the car or carriage, whereby the machine may be sensitively steered and controlled. As shown, each of the said supporting surfaces 13 and 14 consists of a pair of laterally extending wings fixed at their inner ends to the frame structure and reinforced throughout their length therefrom by suitable braces 17. The wings of both the front and the rear supporting surfaces may be conventionally curved and arranged to present a proper angle of incidence for supporting action when the machine is in flight. It will be observed that the supporting surfaces are coextensive in area or dimensions and arranged at points equidistantly from the car or carriage at the center of the machine, and that the wings of each surface are dihedrally-angled or inclined outwardly and upwardly from the frame at an angle of about 15°, the construction and arrangement thus being such that the load weight is carried at the center of the machine and below the plane of the wings

which serve as points of suspension whereby the machine is supported in the air when said machine is in flight. It will thus be understood that as the front and rear supporting surfaces are at a dihedral angle relatively to each other, provision is made for obtaining inherent longitudinal stability, while as the wings of each supporting surface are dihedrally-angled with relation to each other provision is made for obtaining inherent lateral stability. The load weight of the machine being at the same time at a point central and between the supporting surfaces and below the lever thereof, it will be understood that the car will serve as a gravity weight establishing resistance to either lateral or longitudinal deflection of the craft from a state of equilibrium when in flight. The machine is thus rendered self-balancing and, if overturned, as during a storm, will right itself, with proper clearness, allowing a safe descent to the ground or a continuance of flight, as circumstances or judgment of the aviator may deem advisable. It will further be observed that the construction described also provides a machine which may be lightly built in a staunch and durable manner.

I claim:—

30 1. An aeroplane comprising a central car, head and tail frames projecting from the car respectively at an upward and forward angle and at an upward and rearward angle, and supporting surfaces upon said frames

equidistantly from the center of the machine, each of said supporting surfaces comprising a pair of laterally extending wings arranged at an outward and upward angle to each other corresponding to the angular relation of the head and tail frames to each other.

2. An aeroplane including a central car or carriage, head and tail frames projecting upwardly and forwardly and upwardly and rearwardly, respectively, from said car or carriage, said frames being coextensive in dimensions and disposed at like angles to the car and in dihedral relationship to each other, controlling rudders upon said head and tail frames, supporting wheels upon the car and outer ends of the head and tail frames arranged in a common plane, propelling mechanism upon the car, and supporting surfaces upon the outer ends of the head and tail frames at equal distances from the car, said surfaces being of like character and dimensions, each of said surfaces comprising a pair of laterally extending wings arranged at a dihedral angle with relation to each other corresponding to the angular relation of the head and tail frames.

In testimony whereof I affix my signature in presence of two witnesses.

ELMER C. PARSONS.
